SPOON OR SIMILAR ARTICLE OF FLATWARE

Edward J. Conroy, Meriden, Conn., assignor to The International Silver Company, Meriden, Conn., a corporation of Connecticut

Application November 13, 1958, Serial No. 53,367

Term of patent 14 years

(Cl. D54—12)

Fig. 1 is a front elevational view of a spoon showing the essential features of my new design in full lines;

Fig. 2 is an enlarged cross section taken on the line 2—2 of Fig. 1;

Fig. 3 is an enlarged cross section taken on the line 3—3 of Fig. 1; and

Fig. 4 is a side elevational view of the spoon shown in Fig. 1.

The back of the spoon conforms with the disclosures of Figs. 2, 3 and 4.

The design is intended for use on sets comprising spoons, forks, knives and similar articles of flatware.

I claim:

The ornamental design for a spoon or similar article of flatware, substantially as shown and described.
